UNITED STATES PATENT OFFICE.

EDWARD B. WEED, OF CLEVELAND, OHIO.

DESIGN FOR A HANDLE-BAR POST.

SPECIFICATION forming part of Design No. 32,856, dated June 19, 1900.

Application filed May 12, 1900. Serial No. 16,519. Term of patent 7 years.

To all whom it may concern:

Be it known that I, EDWARD B. WEED, a citizen of the United States, residing at Cleveland, in the county of Cuyahoga and State of Ohio, have invented and produced a new and original Design for Handle-Bar Posts, of which the following is a specification, reference being had to the accompanying drawings, forming part thereof.

10 Figure 1 is a perspective view; Fig. 2, a front elevation, and Fig. 3 a sectional side elevation.

The leading or material features of my design consist of a cylindrical stem A, having 15 at its upper end a laterally-extended arm B, from the upper surface of which parallel ver-

tical rounded ears C project, which ears have serrated perforations c, of which one is larger than the other.

As shown, the laterally-extended arm is 20 convex in its lower surface and angular on its upper surface, and its outer end is curved upward and merged into the outer ear.

Having described my invention, I claim—

The design for a handle-bar post substantially as herein shown and described. 25

In testimony whereof I hereunto affix my signature in the presence of two witnesses.

EDWARD B. WEED.

Witnesses:

E. L. THURSTON,
E. B. GILCHRIST.
